SEWING MACHINE

John D. Karle, Roselle Park, N. J., assignor to
The Singer Manufacturing Company, Elizabeth, N. J., a corporation of New Jersey

Application March 25, 1939, Serial No. 264,093

17 Claims. (Cl. 112—181)

This invention relates to sewing machines and more particularly to the stitch-forming instrumentalities of sewing machines.

One of the objects of this invention is the provision of an improved rotary hook which will rotate at a uniform angular velocity, and only 1½ times for each stitch-forming cycle, thereby effecting a 25% reduction in the speed of the hook and its actuating mechanism over the usual 2 to 1 type of hook. This decrease in speed reduces heating of and wear on the bobbin-case flange and the raceway of the hook.

Other objects of this invention are the provision of a balanced hook which may be operated at high speeds without vibration and an improved thread-deflector and pull-off element which has an easy action on the thread and will more effectively deflect the thread and at the same time pull a supply of thread from the bobbin.

With the above and other objects in view, as will hereinafter appear, the invention comprises the devices, combinations and arrangements of parts hereinafter set forth and illustrated in the accompanying drawings of a preferred embodiment of the invention, from which the several features of the invention and the advantages attained thereby will be readily understood by those skilled in the art.

The several features of the present invention will be clearly understood from the following description and accompanying drawings in which:

Fig. 1 is a side elevation of a sewing machine having my invention embodied therein.

Fig. 2 is a bottom plan view of the machine showing the mechanism below the bed-plate.

Fig. 3 is an end elevation of the machine with the face-plate removed.

Figs. 4 and 5 are perspective views showing the hook and the thread-deflector, the thread-deflector being shown in active and inactive position.

Fig. 6 is a face view of the hook.

Figs. 7 and 8 are side views of the hook.

Fig. 9 is a side elevation of the hook and bobbin-case, the hook being shown in section.

Fig. 10 is a disassembled perspective view of the hook.

In the embodiment of this invention selected for illustration, 10 represents the bed-plate of the machine which carries the standard 11 having an overhanging bracket-arm 12 which terminates in a hollow head 13. Journaled in suitable bearings in the bracket-arm 12 is an actuating shaft 14 having a balance-wheel 15 se-

cured to one of its ends and a crank 16 secured to its other end.

Journalized in the bearings 17 carried by the hollow head 13 is a needle-bar 18 carrying a needle 19. The needle-bar 18 is reciprocated in its bearings by means of the link 20 which has one of its ends connected to the crank 16 and its other end operatively connected to the pivot-pin 21 which is secured to the needle-bar 18. Also carried by the hollow head is a presser-bar 22 carrying a presser-foot 23 which is urged downwardly by the spring 24. Also located within the hollow head is the take-up 26 which is actuated by means of the crank 16.

The shaft 14 carries a feed-lift eccentric 28 which actuates a pitman 29 having its lower end connected to a feed-lift rock-shaft 30 for the purpose of imparting a rising and falling movement to the feed-bar 31. A feed-advance eccentric 32 is also carried by the shaft 14 and this eccentric actuates a yoked lever 33 which has its lower end connected to a rock-shaft 34 for the purpose of imparting a feed and return movement to the feed-dog 31. The forward and return feeding movement imparted to the feed-bar 31 may be adjusted by varying the pivot point upon which the lever 33 moves. It will be understood that the feed-bar 31 carries a feed-dog 36 which cooperates with the presser-foot 23 to advance the material through the machine. For a more detailed description of the above described mechanism reference may be had to the patent to Diehl et al., No. 1,146,406, dated July 13, 1915.

Carried by the shaft 14 is a gear 37 which meshes with a gear 38 carried by a vertical shaft 39 which is journalized in suitable bearings in the machine. Carried by the lower end of the shaft 39 is a gear 40 which meshes with the gear 41 secured to one end of a hook-shaft 42. The ratio of the gears 37, 38 is as 1 is to 1 and therefore the shaft 39 makes one complete rotation for each rotation of the shaft 14, and the ratio of the gears 40, 41 is as 1½ is to 1 and therefore the hook-shaft 42 makes 1½ rotations for each rotation of the vertical shaft 39 and the actuating shaft 14.

Fixed to the end of the shaft 42 by the set screws 44 is a hook indicated generally as *a*, (Fig. 10), which cooperates with the needle 19. The hook is preferably formed with a body 45 having two laterally extending flanges 45a and 45b to which is detachably secured, by any suitable means, two arcuate shaped members 46 and 47. These members 46 and 47 are disposed 180°.

apart and are formed with a loop-seizing beak 46' and 47' and a loop-controlling tail 46a and 47a, respectively. The members 46 and 47 are identical in size, shape and weight and each 5 member is formed with a raceway 50 in which is journaled the peripheral bearing rib 51 of the stationary bobbin-case carrier-element 52. The bearing rib 51 of the bobbin-case carrier has the usual gap in its upper portion to provide a loop-10 detaining shoulder 53 (Fig. 9). The bobbin-case carrier 52 is formed with a rotation restraining notch 54 loosely entered by the tongue 55 of the rotation restraining bar 56 mounted on the under side of the bed 10. Removably held 15 in the bobbin-case carrier-element 52 is the bobbin-case element 57 which carries the bobbin 57' of under thread. It is understood that the bobbin-case which carries the under or lower thread mass includes the two separable elements 20 52 and 57.

Fixed to the end of the vertical shaft 39 is a crank 58 which is operatively connected to one end of the reciprocatory shaft 59 by a link 60. The shaft 59 is journaled in the bearings 61 carried by the depending lugs 62 of the bed 10 and secured by the split hub 63 to the shaft 59 is an arcuate member 64 carrying a thread-deflector and pull-off device 65 which acts on the needle and bobbin-thread during each stitch-forming 30 cycle.

A trough-shaped guard 68 is detachably secured to the bearing lugs 62, and the end of the guard beneath the standard is adapted to contain a lubricant, a cover 69 being provided to prevent 35 the lubricant from escaping.

The operation of the machine is as follows: Assuming that the needle 19 has descended through the material and the usual needle-aperture in the throat-plate 66 to its lowest position 40 and has begun its ascending motion, the stitch-forming instrumentalities will then be in the position shown in Figure 4. At this point in the stitch-forming cycle the beak 46' of the rotating hook enters or seizes the needle-loop thrown out 45 by the needle and expands the needle-loop for the purpose of casting it around the lower thread mass or bobbin in the usual manner. After the loop has been seized and the needle has ascended to a point above the thread-deflector and pull-off 50 element 65, this element, through the operative connections above described, is moved laterally to engage the needle-thread N and the under thread U, and after the hook has traveled substantially 180° the thread-deflecting and pull-off element 65 55 has moved to the position shown in Fig. 5. In this position the element 65 has pulled a length of under thread from the bobbin and all of the threads have been deflected out of the path of movement of the hook-beak 47', so that the beak 60 47' may pass the threads without seizing them. When the hook reaches cast-off position, the crank operated take-up 26 begins its quick up-stroke and draws the needle-loop off of the hook-beak 46' and onto the loop-controlling tail 47a. 65 As rotation of the hook continues the needle-loop is released by the controlling tail 47a and the take-up 26 sets the stitch.

While the stitch is being set the hook is given a rotary movement of substantially 180° or 1/2 a revolution. It will be understood that the present hook makes 1 1/2 revolutions for each rotation 70 of the needle-bar shaft or in other words for each needle reciprocation. The feeding of the work and the stitch setting occurs while the 75 needle is out of the work and during stitch set-

ting and feeding the thread-deflector and pull-off 65 is moved, through its connections with the shaft 39, back to the position shown in Fig. 4. It will be apparent from the foregoing description that the shaft 39 makes one rotation for each 5 rotation of the needle-bar shaft and, therefore, the element 65 is vibrated in timed relation with the needle and once for each needle reciprocation.

After the stitch is set the needle again descends through the work and during the early 10 part of its ascending movement throws out a loop and in this stitch-forming cycle the beak 47' seizes the loop and casts it around the lower thread-mass. The stitch-forming action is identical with that above described. 15

From the foregoing it will be understood that the hook is provided with two loop-seizing beaks which are identical in shape and are disposed 180° apart, and the hook is given 1 1/2 rotations for each needle reciprocation so that alternate needle-loops are seized by different beaks. This construction results in a balanced hook and a reduction in speed over the usual 2 to 1 hook of 25%, with its attendant advantages. 20

It will also be understood that the thread-deflector and pull-off 65 is moved laterally of the hook, or parallel to the axis about which the hook rotates, once for each stitch-forming cycle and this element functions to pull off a length of thread from the bobbin and deflects all of the 30 threads to prevent them from being seized by the idle hook-beak. It will be apparent that the thread-deflecting and pull-off device may be used with a loop-taker having only one loop-seizing beak and that it has a gentle action on the 35 threads as it merely pushes them laterally of the line of seam formation. The element 65 also acts as a shield for the hook and keeps it clean and relatively free from lint and other foreign material. 40

From the foregoing description considered in connection with the accompanying drawings, the construction, manner of operation and several advantages of my improved sewing machine will be clearly and fully understood. It is apparent 45 that such a machine has a wide variety of uses, and it will be understood that the form, construction and arrangement of the several elements employed may be varied. Therefore, the privilege is reserved of resorting to all such legitimate 50 changes therein as may be fairly embodied within the spirit and scope of the appended claims. 43

Having thus set forth the nature of the invention what I claim herein is:

1. In combination with a reciprocatory eye-pointed needle, a rotary hook cooperating therewith and having a plurality of loop-seizing beaks, and means for imparting to said hook more than one complete rotation for each reciprocation of the needle. 55

2. In combination with a reciprocatory eye-pointed needle, a rotary hook cooperating with said needle and having two loop-seizing beaks, and means for rotating said hook 1 1/2 times for each needle reciprocation. 60

3. In combination with a reciprocatory eye-pointed needle, a circularly moving loop-taker cooperating therewith and having two loop-seizing beaks disposed substantially 180° apart, and means for rotating said loop-taker 1 1/2 times for each needle reciprocation. 70

4. In combination with a reciprocatory eye-pointed needle, a circularly moving loop-taker coordinated therewith and having a plurality of circumferentially spaced loop-seizing beaks, and 75

- means for imparting to said loop-taker more than one complete rotation for each needle reciprocation.
5. A stitch-forming mechanism for sewing machines comprising an eye-pointed thread-carrying needle, means for reciprocating said needle, a rotary loop-taker cooperating with said needle and having two beaks which are adapted to alternately seize the needle-loop, and means for rotating said loop-taker $1\frac{1}{2}$ times for each needle reciprocation. 5
6. A sewing machine having, in combination, a needle-bar carrying an eye-pointed needle, means for reciprocating said needle-bar, a hook cooperating with said needle, said hook being provided with a plurality of loop-seizing beaks, and means for actuating said hook so that different loop-seizing beaks seize the needle-loop during successive stitch-forming cycles. 10
10. 7. A sewing machine having, in combination, a reciprocating needle, means for reciprocating said needle, a hook cooperating with said needle, a thread-deflector, and means for vibrating said thread-deflector laterally of the hook. 15
20. 8. A sewing machine having, in combination, an eye-pointed thread-carrying needle, means for reciprocating said needle, a rotary hook cooperating with said needle, means for imparting to said hook more than one complete rotation for each needle reciprocation, a thread-deflector and means for vibrating said thread-deflector laterally of the hook during each stitch-forming cycle. 20
25. 9. A sewing machine having, in combination, an eye-pointed thread-carrying needle, means for reciprocating said needle, a rotary hook cooperating with said needle and having a plurality of loop-seizing beaks, means for imparting to said hook more than one complete rotation for each needle reciprocation so that a different loop-seizing beak seizes a needle-loop during successive stitch-forming cycles, a thread-deflector and means for vibrating said thread-deflector laterally of the hook during each stitch-forming cycle. 25
30. 10. A sewing machine having, in combination, an eye-pointed thread-carrying needle, means for reciprocating said needle, a rotary hook cooperating with said needle and having two needle loop-seizing beaks, means for rotating said hook $1\frac{1}{2}$ times for each needle reciprocation, a needle-thread deflector and means for vibrating said thread-deflector laterally of the hook during each stitch-forming cycle. 30
35. 11. A sewing machine having, in combination, an eye-pointed thread-carrying needle, means for reciprocating said needle, a rotary hook cooperating with said needle in the formation of stitches, a stationary bobbin-case carrier-element about which the hook casts the needle-loop during each stitch-forming cycle, a member adapted to engage the needle-thread and bobbin-case thread and means for moving said member laterally of the line of seam formation during each stitch-forming cycle. 35
40. 12. A sewing machine having, in combination, an eye-pointed thread-carrying needle, a shaft for reciprocating said needle, a rotary hook cooperating with said needle in the formation of stitches, a shaft for actuating said hook, means for operatively connecting the needle-bar actuating shaft and the hook actuating shaft so that the hook actuating shaft makes more than one complete rotation for each needle reciprocation, a thread-deflector overlying said hook and means operatively connected to the needle-bar actuating shaft for actuating said thread-deflector laterally of the hook during each stitch-forming cycle. 40
45. 13. A sewing machine having, in combination, a reciprocating eye-pointed needle, a needle-bar shaft for actuating said needle, a rotary hook cooperating with said needle in the formation of stitches, a shaft for actuating said hook, means for operatively connecting said hook-shaft with said needle-bar shaft so that the hook-shaft is given more than one rotation for each rotation of the needle-bar shaft, a shaft located adjacent said hook-shaft, a thread-deflector carried by said shaft and overlying said hook and means connecting said thread-deflector shaft with the needle-bar actuating shaft whereby the thread-deflector is actuated once for each stitch-forming cycle. 45
50. 14. A rotary hook for sewing machines comprising, a body, two members carried by said body and disposed 180° apart, each of said members being formed with a loop-seizing beak and a raceway, and a bobbin-case carrier journaled in the raceways. 50
55. 15. A rotary hook for sewing machines comprising, a body, a plurality of members carried by said body and detachably secured thereto, each of said members being formed with a loop-seizing beak and a loop-controlling tail. 55
60. 16. A rotary hook for sewing machines comprising, a body having a plurality of laterally extending flanges, a member detachably secured to each of said flanges, each of said members being formed with a loop-seizing beak, a loop-controlling tail and a raceway, and a bobbin-case carrier journaled in said raceways. 60
65. 17. A hook for sewing machines comprising a body, a plurality of members detachably secured to said body, each of said members being formed with a raceway and at least one of said members being formed with a loop-seizing beak. 65

JOHN D. KARLE.
